CONVERTIBLE TABLE

Mary A. Boyes, Los Angeles, and J. Edwin Coates, Santa Monica, Calif., assignors to Alta Engineering Company, Santa Monica, Calif., a limited partnership of California

Application December 8, 1947, Serial No. 790,396

2 Claims. (Cl. 311—3)

1

This invention relates to an amusement device for children and more particularly to a mobile frame adapted to serve selectively as a horizontal base for the support of building blocks, small toys, etc., and as a generally upright easel for the reception of cut-out pictures, targets for throwing games, and other amusement purposes. The invention generally contemplates the provision of a planar base member on which a child may assemble building blocks, arrange various stationary and movable toys, and play various marble and ball games, the base being provided with casters or the like so that it can be readily moved about the house.

It is well known that children enjoy playing on the floor and one of the most usual pastimes consists in building towers or houses with a set of blocks. Invariably, such structures are built in the center of a room or a hall and constitute a substantial hazard to adults who find it necessary to walk about the house. They cannot be moved without disassembly, and this is a source of disappointment to the child. The present invention provides a base of considerable area on which the block structures can be erected and, because it is mounted on casters or gliders, it stands only a few inches above floor level so that it is readily accessible to even the smallest child, and cannot be accidentally tipped over. It can be moved at a moment's notice without disturbing anything which may be on it and can be readily stored in convenient places, such as under the child's bed.

In order to facilitate handling, the device is provided with a handle which may be moved from an inoperative position to one where it may be readily grasped while standing, and the cart may then be moved easily in the manner of a baby buggy. In the inoperative position the handle is substantially co-planar with and embraces the base.

The base is generally in the form of a tray with an upstanding marginal edge containing a panel of fairly soft, readily penetrable material such as "Celotex" or other similar wall boards. Cut-out pictures, bases of cardboard model houses, and other things can be readily attached to such a panel with pins or thumb tacks and can be quickly removed when desired. The panel itself can be easily removed and replaced when it becomes worn or damaged.

The handle is so constructed and mounted that it can be moved to a third predetermined position extending angularly away from the rear face of the base to support it in a generally upright

2

position in the manner of an easel. The child can then mount paper on the panel for drawing pictures and the like or attach targets for dart or pin games.

5 Another important feature of novelty is the construction and arrangement of the cooperating parts of the handle and the base which provides for retaining the handle in three different predetermined positions with a minimum amount of structure and no moving parts except the handle itself. Other features of novelty and advantages will become apparent as the description proceeds.

The presently preferred forms of the invention 15 are illustrated in the accompanying drawings in which:

Figure 1 is a top plan view of the device with a portion of the handle broken away;

Figure 2 is a side elevational view of the device 20 with a portion of the handle broken away and showing the supporting casters;

Figure 3 is a sectional view taken on line 3—3 of Figure 1 showing the detent engagement when the handle is in upwardly extending position;

25 Figure 4 is a view similar to Figure 3 but showing the detent engagement when the handle is in inoperative position;

Figure 5 is a sectional view taken on line 5—5 of Figure 1;

30 Figure 6 is a fragmentary perspective view of a portion of the base to which the handle is pivotally attached, the handle being shown in its upper position in full lines and in its lower position in dotted lines;

Figure 7 is a perspective view of the device set up as an easel;

Figure 8 is a fragmentary perspective view of a modified form of the base shown in Figure 1; and

40 Figure 9 is a sectional view taken on line 9—9 of Figure 1.

In the form of the invention shown in Figure 1 the base 10 includes a generally rectangular frame 12 of angular cross section provided with a U-shaped handle 14. The latter is pivotally attached to the frame by means of a pair of stepped stud rivets as best seen in Figure 9. Each of the rivets includes a medial cylindrical section 16 with oppositely extending bosses 18 and 20 of reduced diameter. The boss 18 passes thru an aperture 22 in the frame 14 and is headed over at 24 for rigid attachment thereto. The boss 20 forms a journal for the bearing aperture 26 45 formed in the handle 14 and is headed over at

28 to retain the handle thereon for free pivotal movement.

The frame is reinforced and rigidified, as illustrated in Figure 5, by the provision of a panel 30 of strong rigid material such as "Masonite" altho a thin sheet of steel or other suitable material may be used. This panel forms a fairly close fit within the frame and is permanently secured thereto by a plurality of rivets 32 passing thru aligned openings in the panel and the horizontal portions 13 of the frame. The panel, together with the frame, forms a tray for the reception of toys such as building blocks and the like, and the vertical portions 15 of the frame form a low wall to prevent marbles, balls, or rolling toys from rolling off the base.

The base as described above is complete in itself and is strong enough to support the weight of a child as well as his toys. To increase the utility of the device, a second panel 34 is provided. This panel, of substantially the same size as panel 30, is formed of a fairly soft, readily penetrable material such as "Celotex" or other wall board and is detachably secured to panel 30 by means of a plurality of headed pins 36 having cotter pins 38 passing through their lower free ends. The soft material is readily penetrated by pins or thumb tacks which may be used to attach paper cutouts of any desired type thereto. Panel 30 will become worn or damaged in time and the connection described facilitates detachment and replacement with a new panel.

The U-shaped handle 14 is of such size and shape that, in its inoperative position as shown in dotted lines in Figure 1, it embraces the major portion of the frame 12. The free ends 40 of the handle are bent out of its general plane at an angle of approximately 45 degrees, and the bearing aperture 26 in each leg is located approximately at the point of bending, altho such location is not absolutely essential.

The ends 40 are chamfered and the tips 42 thereof are bent inwardly as shown to serve as detents. Detent receiving portions 44 and 46 are formed in the vertical side walls 15 of the frame and may be dimples or depressions, but it has been found more desirable to form them as apertures passing entirely through the walls 15. When the handle 14 is in the position shown in Figure 2, extending upwardly and away from the front face of the base at an angle of approximately 45 degrees the detents 42 extend into apertures 44 as best illustrated in Figure 3, and the handle may be grasped to move the base from place to place. When it is desired to swing the handle about its pivotal mounting to a new position the detents can be readily sprung out of the apertures by a forceful movement of the handle since the ends 40, or the entire handle if desired, are formed of resilient material.

When the handle is swung clockwise as viewed in Figure 2 it will come to rest in the dotted line position shown in that figure. When the handle reaches this position the detents 42 will bear against the lower marginal edges of the frame as indicated in Figure 4, and prevent the handle from falling lower.

The handle may also be swung to a position extending away from the rear face of the base at an angle of approximately 30 degrees to support the base in a generally upright position on a floor in the manner of an easel, as illustrated in Figure 7. In this latter position the detents 42 are sprung into engagement with the detent receiving portions 46 to releasably retain the handle

5 against unintentional movement. With this arrangement a child can mount cutouts of any kind on the panel 34 by means of pins or thumb tacks and may attach a target for a throwing game such as the target 48.

10 The relation and cooperation of the main portions of handle 14, the free ends 40, detents 42, and detent receiving portions 44 and 46 are clearly illustrated in Figure 6, in which the handle is shown in its upwardly extending position in full lines and in its lower or easel position in dotted lines. It will be noted that, because the apertures 44 and 46 are not directly in line with the mounting pivot and the detents 42 are correspondingly offset, the angular divergence of the handle is greater in the upper position than in the lower position.

15 It is desirable to support the base some distance above the floor for ease of use but it should be low enough to prevent tipping if a child sits on it and also low enough to be stored under articles of furniture such as a bed. It should also be easily movable on the floor. These conditions are met by the provision of casters 50 having base 20 plates 52 attached to the horizontal portions 13 of frame 12 by means of rivets 54. It will be seen that, with the handle 14 in the position shown in Figure 2, the device may be readily wheeled about by grasping the cross bar 17 of the handle. The 25 casters are located inwardly from the end edges of the frame a sufficient distance to prevent them from contacting the floor when the device is used as an easel.

30 A modified form of the base is illustrated in Figure 8, in which it is formed of a single sheet of metal providing a rectangular web member 56 with upwardly extending integral flange members 58 on all four sides. An X-shaped depression 60 is stamped in the web member to 35 strengthen and rigidify it. It is thus possible to dispense with a separate strengthening panel such as member 30. However, a detachable, penetrable panel is provided as in the previously described modification and the handle and caster 40 details may be similar or identical to those already described.

45 It will be seen that we have provided a novel and easily operable amusement device having many uses and advantages. Various changes 40 and modifications may be made in its construction without departing from the spirit of the invention, and it is intended that all such changes and modifications shall be embraced within the 50 scope of the following claims.

55 We claim:

1. A child's play table comprising: a generally 55 rectangular tray member, substantially longer than it is wide, presenting an upper surface; a relatively shallow flange upstanding from the edges of said tray member to rigidify same and serve as a guard rail for objects; support members attached to said tray member and extending downwardly therefrom; a generally U-shaped bail having arms substantially longer than one-half the length of said tray member; said arms being pivotally attached near their free ends to the flange on the long edges of said tray member at such points that the bail, in inoperative position, will lie in close juxtaposition to said flange 60 thruout the length of the bail; cooperating detent means on said arms and said flange engaging each other in a first relation to hold said bail in inoperative position, said bail being 65 swingable to an adjusted position behind said tray member to cooperate with a short edge 70

thereof to support said upper surface in an angular attitude with respect to a supporting surface; said detent means engaging each other in a second relation to retain said bail in said adjusted position.

2. A child's play table as claimed in claim 1, said bail being swingable to a position above said tray member to serve as a hand grip to move said tray member about on a supporting surface; and said detent means engaging each other in a third relation to retain said bail in said further adjusted position.
